CLAIM

The ornamental design for a pill box, as shown and described.

DESCRIPTION

FIG. 1 is a top perspective view of a pill box showing my new design;

FIG. 2 is a bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is an exploded perspective view thereof.

The broken lines shown are included for the purpose of illustrating unclaimed portions of the article and form no part of the claimed design.
